INVENTOR

Fred H. Henry,
By his Atty.
Henry W. Williams

UNITED STATES PATENT OFFICE.

FRED H. HENRY, OF WAKEFIELD, MASSACHUSETTS.

CAR-SEAT.

SPECIFICATION forming part of Letters Patent No. 425,424, dated April 15, 1890.

Application filed April 20, 1889. Serial No. 308,014. (No model.)

To all whom it may concern:

Be it known that I, FRED H. HENRY, of Wakefield, in the county of Middlesex, in the State of Massachusetts, have invented a new and useful Improvement in Car-Seats, of which the following is a specification.

This improvement relates to that class of car-seats in which the reversible seat-back is locked when it is dropped into position by gravity, and when it is in such position does not drop behind the seat, but remains with its lower edge above or substantially on a level with the surface of said seat.

In the accompanying drawings, in which similar letters of reference indicate like parts, Figure 1 is an end elevation of a car-seat embodying my invention, portions being broken out the better to illustrate the same, and the two positions of the seat-back being represented in full and broken lines. Fig. 2 is an enlarged sectional detail showing the operation of the device. Fig. 3 is a section on line $\alpha\alpha$, Fig. 2.

A represents the frame, of which A' is the arm, and B an upright or post, by means of which the seat-back is supported and over which it swings.

C is the cushion of the seat, and D the back. E is a plate secured to the frame D' of the seat-back, and provided with an integral disk-shaped tongue E', said tongue having on its periphery two notches e e. This plate is chambered out on the line of a circle on each side at E''.

H is the back arm or striker-arm, one end of which is pivotally secured at b to the post or upright B, the other end being made thicker at H' and bifurcated or split at h, and shaped, as shown, so that the two outer ends of the bifurcated portion are circular or disk-shaped at H'', and being secured by means of the pivot I to the disk portion E' of the plate E, fit into the circular recesses or chambers E''. Pivotally secured within the bifurcated portion of the arm H at h is a pawl K, provided with two teeth K' of substantially the shape shown.

When the seat-back is in the position shown in full lines in Fig. 1, the pawl, having dropped by gravity, is in the position shown in Fig. 2—that is, with its upper tooth K' in engagement with the upper notch e on the periphery of the disk-shaped tongue E. (See Fig. 2.) When the seat-back is reversed, the pawl K drops by gravity, releasing the notch above

mentioned as being in engagement, and engaging by means of its other tooth K' the other notch e and allowing the seat-back to assume the position shown by broken lines in Fig. 1. It will be noticed that the angle is 60 the same in both cases and the seat-back is prevented from dropping behind the seat directly by the pawl K and notched disk E'.

The means of the pivotal support of the inner end of the back arm or striker-arm H 65 is not described in detail, as it is not new in this invention. It is found in practice that in car-seats of this style—that is, in which a reversible seat-back is locked by a gravity-pawl when it is dropped into position—the 70 pawl not infrequently sticks, from one cause or another, and does not drop and lock the seat. In this invention the pawl by being in the position shown is in plain sight and readily accessible, so that if it fails to drop 75 by gravity from any cause it can be readily pushed into position by the finger. This of course cannot be done where the pawl is boxed in out of sight and out of reach. The relative position of the pawl is such that it 80 can be made very strong, has a long leverage, and the bearing is directly on its end and on a line with its length.

Having thus fully described my invention, what I claim, and desire to secure by Letters 85 Patent, is—

In a car-seat, the combination of the following parts, viz: the plate E, secured to the frame of the seat-back, the tongue E', integral with said plate, notched at e e, and 90 with the portion of its edge or periphery which extends from the seat-back of even thickness with its central or body portion, the striker-arm H, pivotally secured to the post B, extending up from the seat-frame, 95 said striker-arm being bifurcated or cored out at h, and the double-acting gravity lever or pawl K, provided with the teeth K', pivoted in said bifurcation and swinging in and out of the same in plain sight, and accessible on both sides of said striker-arm, the ends H'' of the bifurcated portion of said striker-arm being pivotally secured to the portion E' of 100 said plate, all constructed and arranged substantially as set forth.

FRED H. HENRY.
